FIG. 1

FIG. 4

FIG. 2

FIG. 3

FIGURE 1 is a perspective view of a ventilating fixture showing my new design in closed position.

FIGURE 2 is a perspective view thereof in open rotated position.

FIGURE 3 is a perspective view thereof in an inclined open position.

FIGURE 4 is a side elevational view thereof in an open rotated position.

The top of the dome-shaped housing is open. The side not shown is substantially the same in appearance as that shown.

The dominant features of my design for a ventilating fixture reside in the portions shown in full lines.

I claim:

The ornamental design for a ventilating fixture, as shown and described.
